[57] CLAIM

The ornamental design for a rodless cylinder with position detector and brake, as shown and described.

DESCRIPTION

FIG. 1 is a front elevational view of a rodless cylinder with position detector and brake embodying our new design;
FIG. 2 is an elevational view of the right side thereof;
FIG. 3 is a top plan view thereof;
FIG. 4 is an elevational view of the left side thereof;
FIG. 5 is a rear elevational view thereof;
FIG. 6 is a bottom plan view thereof; and,
FIG. 7 is a perspective view thereof.
